UNITED STATES PATENT OFFICE.

STANLEY GADOMSKI, OF CHICAGO, ILLINOIS.

DESIGN FOR A FLAG.

Application filed May 31, 1922. Serial No. 2,475. Term of patent 7 years.

To all whom it may concern:

Be it known that I, STANLEY GADOMSKI, a citizen of the United States of America, residing at Chicago, in the county of Cook and State of Illinois, have invented a new, original and ornamental Design for a Flag, of which the following is a specification, reference being had to the accompanying drawing, forming part thereof.

The figure is a front elevational view of a flag, showing my new design.

I claim:—

The ornamental design for a flag, as shown.

STANLEY GADOMSKI.
